UNITED STATES PATENT OFFICE.

SANFORD W. BROTHERS, OF DENVER, COLORADO.

ROCK-DRILL.

No. 927,940.

Specification of Letters Patent. Patented July 13, 1909.

Application filed April 9, 1907. Serial No. 367,268.

To all whom it may concern:

Be it known that I, SANFORD W. BROTHERS, a citizen of the United States, residing at the city and county of Denver and State 5 of Colorado, have invented certain new and useful Improvements in Rock-Drills; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 My invention relates to improvements in rock drilling machines and relates to certain novel features of construction, all of which will be fully understood by reference to the accompanying drawing in which is illustrated an embodiment thereof.

In this drawing, Figure 1 is a vertical longitudinal section taken through my improved machine. Fig. 2 is a top plan view of the same with the drill steel removed. 25 Fig. 3 is a section similar to Fig. 1. The mechanism, however, is partly broken away and shown on a larger scale. Fig. 4 is an enlarged sectional view of the rear portion of the drill. This view shows the part 30 broken away in Fig. 3. Fig. 5 is a cross section taken on the line 5—5 Fig. 1. Fig. 6 is a sectional view showing the forward extremity of the drill casing. Fig. 7 shows the pipe passed centrally through the drill 35 for introducing water to the drill hole. Fig. 8 is a sectional view of the body of the drill showing the body of the casing and the operating parts inclosed thereby. Figs. 9, 10. and 11 are cross sections taken on the lines 40 9—9, 10—10 and 11—11, respectively of Fig. 1.

The same reference characters indicate the same parts in all the views.

Let the numeral 5 designate the body of the drill casing and 6 the forward member of the casing, the two casing parts being connected by rods 7 passed through lugs 8 and 9 on the body of the casing and lugs 10 on the member 6. These rods are threaded 50 into the lugs 9 while nuts are applied to their opposite extremities and seated against the lugs 8 and 10 thus securely fastening the casing members in the assembled relation. In the forward member of the casing, is inserted from the rear a bushing 12 having a

shoulder 12^A engaging an offset formed on the casing member. Into the rear extremity of this bushing 12 is screwed a sleeve 13 whose rear extremity is engaged by a packing collar 14. The sleeve 13 is interiorly 60 grooved to receive tongues 15 formed on the forward reduced part 16 of the hammer 17.

Inserted in the forward extremity of the casing member 6 is a chuck 18 whose rear extremity is exteriorly threaded to engage 65 interior threads formed on the forward extremity of the bushing 12. By virtue of this construction the chuck is connected with the said bushing and is made to rotate with the hammer. The forward extremity of the 70 bushing 12 engages a shoulder 19 formed on the chuck. The chuck is retained in the forward extremity of the member 6 by a nut 20 screwed into interior threads formed on the said member, the said nut having a 75 shoulder 21 which engages the same. The inner extremity of the nut 20 is located in front of a shoulder 22 formed on the chuck. In the rear of the chuck is located a cap 23 having a forward recess 24 adapted to receive the rear extremity of the drill steel 25. This drill steel is angular in cross section and the opening in the chuck together with the recess 24 of the cap are made of counter- 80 part shape whereby the rotation of the chuck 85 also rotates the drill steel. Between the chuck and the cap 23, is a space 26, to allow the necessary range of movement for the drill steel during the operation of the machine. The forward extremity 27 of the 90 body of the drill casing, overlaps the rear part 28 of the casing member 6. Hence when the connecting rods 7 are applied the two members are locked securely together. Within the forward portion of the part 27 95 is located a steel washer 29 which engages the rear extremity of the casing member 6, together with the corresponding extremity of the bushing 12. This steel washer also bears against the collar 14 and its opening 100 is made sufficiently large to allow the hammer member 16 to pass loosely therethrough, the opening in the washer being plain. The forward part of the collar 14 is also surrounded by the steel washer 29; while in the 105 rear of the last named washer is located a rubber buffer 30 and in the rear of the latter, a steel washer 31. This mechanism affords a buffer adapted to engage a forward shoulder 32 formed on the larger portion of 110

the hammer, in case the latter for any reason shall move forwardly a sufficient distance to require a buffer element.

The numeral 17 designates the body or larger portion of the hammer and this portion fits closely within the cylindrical chamber 33 of the casing body. The hammer is also provided with packing rings 34 in order to make a fluid tight joint. The rear portion of the hammer is bored from the rear to form a central opening 35, to allow the rifle bar 36 to enter the same and impart the rotary movement to the hammer during the reciprocation of the latter.

In the rear extremity of a counter bore formed in the hammer is also threaded a bushing 37, the latter being provided with spiral tongues adapted to engage the counterpart grooves of the rifle bar 36. The forward portion of this rifle bar enters the hammer when the latter is at its forward limit of movement, while its rear portion passes through the rear portion of the casing chamber and is supported by a steel washer 38 in the rear of which is located a rubber buffer 39, the latter being surrounded by a buffer spring 40, in the rear of which is another steel washer 60. Formed integral with the rear extremity of the rifle bar is a pawl holder 41 which is surrounded by a ratchet ring 42 threaded into the forward extremity 43 of the rear casing cap 44 which is provided with a shoulder 45 abutting against the rear extremity of the casing. This cap retains the rifle bar and its pawl holder in operative relation within the casing. In the rear extremity of the cap 44 is formed a threaded opening 46 into which is threaded the rear cylindrical head 47 of a fluid delivery pipe or tube 48, the said head being exteriorly threaded to engage the threads of the cap whereby the said tube is secured in place. This head is provided with a central bore registering with the passage of the tube. The pawl holder 41, the rifle bar 36, the hammer 16 and the drill steel cap 23, are provided with central registering openings adapted to receive the water delivery tube. The forward extremity of this tube terminates immediately in the rear of the drill steel 25, the latter being provided with a central passage, to allow the fluid escaping from the forward extremity of the tube, to pass through the drill steel to the bottom of the drill hole.

The reciprocating movement may be imparted to the hammer in any suitable manner. As shown in the drawing the machine is equipped with valve mechanism 49 for delivering motive fluid alternately to the casing chamber in the front and rear of the enlarged or body portion of the hammer, the said fluid entering the chamber by way of ducts 50 and 51. However, as nothing is claimed on this part of the mechanism in this

application, the same will not be described in detail, but it will be taken for granted that the mechanism is equipped with suitable means for reciprocating the hammer by a motive fluid agent. Assuming then that the hammer is reciprocated, it will be understood, that as it moves in one direction, namely toward the rear, a partial rotary movement will be imparted thereto through the instrumentality of the rifle bar, the pawl holder 41 and the ratchet ring 42, since the element 41 carries pawls 52 held in operative relation with the teeth of the ratchet ring 42 by spring pressed pins 53 seated in recesses formed in the part 41. This rotary movement of the hammer will also impart a corresponding movement to the bushing 12, the chuck 18 and the drill steel by virtue of the construction heretofore described.

The drill casing is slidably mounted on the guide shell 54 and is moved back and forth thereon by a feed screw 55 provided with a hand crank 56 in the usual manner.

Attention is called to the importance of the cap 23. This cap is not only provided with the recess for holding the drill steel 25 but also receives the stroke from the hammer and preserves the drill. Another, and very important function that this cap performs is the supporting means for the free or forward portion of the fluid delivery tube 48. It acts as a guide and support to keep the tube 48 in proper alinement during the reciprocation of the hammer. The tube 48 is also supported by the cap 23 whether or not the drill is being operated. It is also immaterial whether the drill steel 25 is inserted. In all other drills so far as I am aware, during the return stroke of a hammer, a third if not half of the fluid tube is unsupported, and it has been impossible to keep the tube in proper alinement and prevent breakage thereof as is very frequent. This cap 23 overcomes all of these difficulties, and the fluid tube very seldom has to be replaced. Besides taking care of the tube 48 it also preserves and carries the drill steel 25.

Having thus described my invention, what I claim is:

1. In a rock drill, the combination with a casing of a drill steel, a reciprocating hammer in alinement therewith, a rifle-bar in operative relation with said hammer the said bar and said hammer having centrally arranged, longitudinally disposed registering passages, a fluid delivery tube extending through said passages, a head-cap for said casing, said tube having a terminally enlarged portion removably engaging said head-cap, the other terminal of said tube having an apertured cap in direct contact therewith, said drill steel being provided with a longitudinal bore which is in alinement with said tube and the aperture of said cap.

2. In a rock drill, the combination with
a casing, of a drill steel, a reciprocating
hammer in alinement therewith, a rifle-
bar in operative relation with said ham-
mer, the said bar and said hammer having
centrally arranged, longitudinally disposed
registering passages, a fluid delivery tube
extending through said passages, said ham-
mer having peripheral tongues, a bushing
disposed in the casing and having grooves
complemental with said tongues, a sleeve in-
ternally screw-threaded at opposite ends, a
chuck having a medial annular projection
and screw threads on one side of said pro-
jection, said sleeve being connected to said
bushing at one terminal and to said threaded
side of the chuck at the other terminal, a nut
having a collar on its outer end and secured
to the casing intermediate the latter and the
other terminal of the chuck, said tube having
an apertured cap in direct contact therewith,
and said drill steel being provided with a
longitudinal bore which is in alinement with
said tube and aperture of said cap. 20
